UNITED STATES PATENT OFFICE.

MATTHEW R. FEELEY, OF SCRANTON, PENNSYLVANIA, ASSIGNOR TO B-S MANUFACTURING PRODUCTS CORPORATION, OF JERSEY CITY, NEW JERSEY, A CORPORATION OF NEW JERSEY.

EIGHT-IMPULSE FOUR-CYLINDER LOCOMOTIVE.

Application filed July 13, 1925. Serial No. 43,344.

To all whom it may concern:

Be it known that MATTHEW R. FEELEY, a citizen of the United States, residing at Scranton, in the county of Lackawanna and State of Pennsylvania, has invented certain new and useful Improvements in Eight-Impulse Four-Cylinder Locomotives, of which the following is a specification.

The present invention relates to locomotives of the steam type, and more particularly to an improved driving means therefor.

An object of the present invention is to provide a locomotive driving mechanism wherein may be obtained, by the use of four high pressure single expansion cylinders, eight successive impulses imparting a practically constant torque; and wherein may be positioned at all times three of the cylinders 20 for overcoming the inertia of starting with but one cylinder only in a dead center or ineffective position.

Another object is to uniformly distribute the weight and power throughout the driving mechanism, and to operate the entire mechanism simultaneously, to not only obtain greater tractive effort and a substantially uniform pressure, but also to reduce vibration; admit of a light yet durable construction; and to admit operation and to eliminate slipping with a low factor of adhesion.

Other objects are to provide a driving mechanism of this character, which may be applied to any class of locomotive for road and yard service, which admits of adaptation to short wheel bases for traversing sharp curves, such as sixteen degree curves; in which the mechanism is so arranged that, after proper acceleration, some of the cylinders may be cut out of operation to economize in consumption of steam; in which steam may be independently and collectively admitted to the cylinders in pairs; which may be easily adapted for use with different types of driving cylinder arrangements, such as with single and compound cylinders; which has its parts interchangeable and relatively small; which admits easy access to the various parts without removing valve gear and other mechanisms as has heretofore been the case; and with which the use of boosters and the like may be eliminated.

A still further object of this invention is

to provide a driving structure of this character which has all of its driving wheels interconnected, with certain of the driving wheels coupled together at substantially forty-five degrees apart for effecting a stepped or timed impulse with respect to the several cylinders employed; and to provide four cylinders and interconnected driving wheels associated therewith to obtain eight impulses cooperating simultaneously to produce a constant driving pressure which is 65 equally distributed throughout the entire mechanism at all times during the cycle of operation.

This invention further aims at the provision of a device possessing all of the above 70 features, and which is composed in the main of standard parts; which does not require a special construction of locomotive; which is capable of economical production and application; which may be applied with but slight 75 minor modifications to practically all types of locomotives now in general use, and in course of construction; and which may be maintained in operation even after breakage occurs to some of the parts by providing means for cutting out either set of cylinders, the construction being so arranged that the sets of cylinders may be operated independently of each other so that the locomotive may remain in service for the remainder of the trip.

A still further object is to provide a condensed construction, differing radically from the mallet type of locomotives; and wherein is obtained in a short wheel base added 90 rigidity, and the desired pressure now obtained only in large and cumbersome locomotives.

The above and various other objects and advantages of this invention will in part be 95 described in, and in part be understood from, the following detailed description of the present preferred embodiment thereof, the same being illustrated in the accompanying drawing, wherein:—

Figure 1 is a side elevation of one type of locomotive equipped with a driving mechanism constructed according to the present invention, and

Figure 2 is a detail bottom view of the 105 running gear with parts broken away and parts removed for the sake of clearness.

Referring to the drawing, the invention is

illustrated in connection with the Mikado type of locomotive, although it is to be understood that this is only for the purpose of illustration as the invention is applicable to various types of locomotives.

The superstructure of the locomotive is indicated at 10, and according to the present invention the superstructure 10 is mounted upon a frame 11 which extends lengthwise therebeneath and is provided with the desired number of driving wheels 12, and other mechanisms incident thereto. At the forward end of the frame 11, the locomotive is provided with a pair of front cylinders 13, one disposed at each side of the locomotive, and at the rear end of the frame 11 a second pair of rear cylinders 14 is mounted, one at each side of the locomotive. A steam line 15 leads in the usual manner to the front cylinders 13 and their associated valve mechanism; the latter being of common construction and only generally illustrated. For the purpose of supplying steam to the rear cylinders 14 and their associated valve mechanism, a connection 16 is taken from the front steam line 15 and a steam pipe 17 is led therefrom along each side of the boiler and superstructure 10 to the rear cylinders 14, although this connection may be otherwise suitably disposed to meet conditions of installation and design. The admission of steam to the front cylinder steam line 15 is accomplished by a throttle valve or the like in any well known manner common to all types of locomotives. The rear cylinder steam supply pipes 17 are each provided, at a suitable intermediate point, with a separate throttle valve 18 which may be controlled by air pressure from a line 19 extending from a convenient point within the cab where may be located a control valve 20 for manual operation to permit the operator to cut in and cut out, at all speeds, the rear cylinders 14, in lieu and in the manner, of a booster to effect economy when the desired acceleration of the locomotive is attained.

The steam from the front cylinders 13 is exhausted in the ordinary manner, but the exhaust from the rear cylinders 14 is conducted through a branch exhaust pipe 21 to the exhaust cavities of the front cylinders 13. This construction provides a more uniform exhaust; and permits the use of a larger exhaust pipe, and reduces the back pressure in the cylinders. The exhaust from either or both pairs of the front and rear cylinders 13 and 14 may be otherwise utilized for different types of drive, such as in locomotives of the compound type.

The steam distribution is so arranged that all four cylinders may be operated simultaneously and are so connected to the driving wheels 12 as hereinafter described in detail that the eight impulses obtained are

consecutive and so follow that a constant torque on the driving wheels is obtained and a uniform driving pressure is assured.

Each pair of front and rear cylinders 13 and 14 is provided with the usual guides 22 and cross heads 23 mounted therein, the latter being connected by piston rods 24 with pistons 25 in the respective cylinders 13 and 14. These guides 22 are arranged preferably in longitudinal and horizontal alignment, and extend toward each other at the opposite sides of the frame 11, and also are disposed in parallelism with the frame.

The driving wheels 12 are arranged in any desired number at opposite sides of the frame 11, and the front and back driving wheels are mounted in pairs on straight axles 26. The intermediate driving wheels 12 are mounted upon double cranked driving shafts 27, the crank portions of which lie between the side bars of the frame 11 and the corresponding crank portions of the shafts 27 are connected together by inside connecting rods 28 which interconnect all of the driving wheels 12. The front and rear driving wheels 12 are interlocked to the intermediate driving wheels by outer side rods 29.

The cross heads 23 are connected by main rods 30 to the main crank pins 32 of the intermediate driving wheels 12. One pair of the main crank pins 32, associated with one of the sets of cylinders 13 or 14, is set on its driving wheels 12 approximately forty-five degrees ahead of the other pair of main crank pins 32 to insure the eight consecutive impulses and the constant torque on the driving wheels 12. The main crank pins 32 of each pair of driving wheels 12 may also be angularly offset in the usual manner.

Accessory to each pair of front and rear cylinders 13 and 14 is a suitable valve gear 33 of any adaptable type; the valve gear 33 of the rear cylinders 14 being arranged reversely or oppositely to the valve gear 33 of the front cylinders 13, and a reversing shaft 34 is coupled to the valve gears 33 by suitable reach rods 35 to simultaneously control the shifting of the valve gears 33. The valve gear 33 of the front pair of cylinders is direct while the valve gear 33 for the rear pair of cylinders is indirect for more regularly developing an even flow of power to the driving wheels. To shift the valve gears 33 a main reach rod 36 is connected to the reversing shaft 34 and extends to a reversing gear cylinder 37 controlled by air pressure from the cab as shown.

The crank pins 32 on the opposite sides of each wheel and axle set are set at 90° apart, while the crank pins of the front pairs of wheels are set on each side at 45° to the crank pins of the rear pairs of wheels, which would result in the crank pins of the adjacent intermediate axles, driven respec-

tively, by the front and rear cylinders, being set at 45° in advancement, the relation being for instance, the front cylinders driving the cranks at 0° and 90° and the rear cylinders the cranks at 45° and 135° . The pistons 25 are all arranged in different degrees of advancement from one another so that but one piston at a time can stop in a dead center position. This insures that there are always 10 three cylinders in working position to transmit pressure in overcoming the inertia of starting.

After the desired acceleration of the locomotive is reached the throttle valve 18 may be closed to cut off the steam supply to the rear cylinders 14 when the consumption of steam is reduced, and still all of the driving wheels 12 are positively driven from the front cylinders 13 as all of the driving 20 wheels 12 are interconnected. The pressure is evenly distributed to all of the driving wheels 12 and there is maintained a proper balance and pressure throughout the length of the locomotive and vibration is 25 reduced to a minimum.

It is obvious that various changes and modifications may be made in the details of construction and design of the above specifically described embodiment of this invention without departing from the spirit thereof, such changes and modifications being restricted only by the scope of the following claims:—

What is claimed is:—

- 35 1. An eight impulse four cylinder locomotive comprising front and rear pairs of cylinders, intercoupled driving wheels, and independent connections between the cylinders and the driving wheels disposed upon the intercoupled driving wheels in offset relation at substantially forty-five degrees.
- 40 2. An eight impulse four cylinder locomotive comprising a series of inter-coupled driving wheels maintained in a predetermined relation relative to one another, a pair of cylinders connected to a pair of the driving wheels for transmitting pressure to the entire series of driving wheels, and a second pair of cylinders connected to another pair of the driving wheels for transmitting pressure to the entire series of driving wheels, said last named connection being

disposed in offset relation at substantially forty-five degrees with respect to the first mentioned connection.

55

3. An eight impulse four cylinder locomotive comprising a series of pairs of driving wheels, means for inter-coupling said pairs of driving wheels in predetermined angular positions, a pair of cylinders connected to a pair of the driving wheels in angular offset relation, a second pair of cylinders connected to another pair of driving wheels in angular offset relation, and means interconnecting said pairs of connected driving wheels with the cylinder connections thereof advanced substantially forty-five degrees, one from the other.

65

4. In a locomotive, a series of pairs of driving wheels, independent impulse means connected to different pairs of the driving wheels and with the connections disposed one substantially forty-five degrees ahead of the other.

70

5. In a locomotive, a series of pairs of driving wheels, front and rear cylinders arranged at the forward and rear ends of the series of driving wheels, independent connections between the front and rear cylinders and the adjacent pairs of driving wheels, and inter-connections between all of the pairs of driving wheels to maintain the front and rear driving connections substantially 45° apart and for transmitting uniformly pressure from said cylinders to all of the driving wheels and for effecting a push and pull pressure throughout the series of driving wheels.

75

6. An eight impulse four cylinder locomotive comprising front and rear pairs of cylinders, inter-coupled driving wheels, independent connections between the cylinders and the driving wheels disposed upon the intercoupled driving wheels in offset relation at substantially forty-five degrees, direct front valve gear for the front pair of cylinders, and indirect valve gear for the rear pair of cylinders for more regularly developing an even flow of power to the driving wheels.
